UNITED STATES PATENT OFFICE.

HARRY L. GILL, OF URBANA, ILLINOIS, ASSIGNOR TO LEAVITT MFG. COMPANY, OF URBANA, ILLINOIS, A CORPORATION OF ILLINOIS.

DISCUS.

Application filed July 11, 1922. Serial No. 574,321.

To all whom it may concern:

Be it known that I, HARRY L. GILL, a citizen of the United States, residing at Urbana, in the State of Illinois, have invented **5** certain new and useful Improvements in Discuses; and I do hereby declare the following to be a full, clear, and exact description of the invention, such as will enable others skilled in the art to which it appertains to **10** make and use the same.

This invention relates to improvements in a discus, such as is ordinarily used in sports and games of skill, and has for its principal object the construction of such a **15** discus, which shall be of solid construction, composed of a minimum of parts and not liable to become disassembled even though subjected to extremely rough usage.

A further object of the invention is the **20** provision of a discus which when thrown will have a regular and even motion through the air and maintain a perfect equipoise at all times.

Another important object of the invention **25** is the provision of improved means for attaching an outer metal rim to the wooden core of a discus, whereby the outer rim will be securely fixed thereto, and which will obviate the necessity of first heating **30** the rim and then shrinking the same onto the core as has previously been done.

Other and further important objects of the invention will be apparent from the disclosures in the accompanying drawings **35** and following specification.

The invention, in a preferred form, is illustrated in the drawings and hereinafter more fully described.

In the drawings:

40 Figure 1 is a plan view of the improved discus of this invention.

Figure 2 is a sectional view of the same.

As shown in the drawings:

The reference numeral 10 indicates the **45** core or body of the discus, which is usually of wood but which may be of any other material as desired. The core is tapered toward its periphery as shown in the drawings, and as is usual in constructions of **50** this sort.

Both faces of the core are slightly flattened and upon these flattened faces are attached circular plates 12 of brass or any other suitable metal. These plates are fixed **55** in position by means of a plurality of screws

as shown at 14. These screws extend only for a relatively short distance into the material of the core, thereby rendering the plates 12 independent of each other and affording a very secure connection between **60** the plates and the material of the core itself.

A circular metal rim 16 binds the outer edge of the discus. As shown at 18, the inner face of the metal rim 16 is provided **65** with tapered screw threads, and the outer rim of the central core 10 is likewise provided with corresponding tapered threads. This provides a means whereby the outer rim 16 may be securely attached to the core **70** 10 and an adhesive substance, such as glue, shellac or the like, may be used in order to firmly bind the rim on to the core 10 by means of the screw threads 18.

It will be seen that herein is provided a **75** discus which can be made absolutely accurate both as to size and weight so as to conform exactly to the rules of the leading athletic associations of the United States and foreign countries. Further, the construction herein illustrated is a particularly **80** simple one and provides a device which can be used for an indefinite length of time without becoming loose or subject to rattling or wearing unevenly in portions **85** thereof.

The threaded construction whereby the outer rim is attached to the central core provides a connection that will at all times remain tight and cannot fall off. The plates **90** 12 are also so attached that there is no possibility of their becoming loose or even of shrinking or warping away from the body of the discus. In addition, the use of a waterproof cement to supplement the tapered screw threaded attachment of the outer rim will insure a very substantial and therefore desirable construction.

I am aware that many changes may be made and numerous details of construction **100** varied throughout a wide range without departing from the principles of this invention, and I therefore do not purpose limiting the patent granted hereon otherwise than as necessitated by the prior art. **105**

I claim as my invention:

1. A discus comprising in combination, a tapered central core comprising a unitary solid block of wood, circular metallic side plates affixed to said core on opposite sides **110**

thereof, and means for maintaining said plates in position, said means comprising screws of a length less than one half the maximum thickness of said core.

5 2. A discus comprising in combination, a tapered central core, a circular side plate affixed to the center of each face of said

core, and fastening means for the plates, said fastening means comprising screws extending into the core toward each other but of such length as to preclude contact.

In testimony whereof I affix my signature.

HARRY L. GILL.
